(57) **CLAIM**

The ornamental design for a hub clock, as shown and described.

DESCRIPTION

FIG. 1 is a perspective view of a hub clock embodying my design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken line disclosure is understood to be for illustrative purposes only and forms no part of the claimed design.
